RECTIFIER COOLING SYSTEM

Stefan Widmer, Baden, Switzerland, assignor to
 Aktiengesellschaft Brown Boveri & Cie., Baden,
 Switzerland, a joint-stock company of Switzerland

Application July 21, 1932, Serial No. 623,797
 In Germany July 30, 1931

4 Claims. (Cl. 250—27.5)

This invention relates to improvements in electric current rectifiers of the metallic vapor arcing type and more particularly to means for maintaining such rectifiers at the most favorable operating temperature.

It is well known that the temperature of an electric current rectifier of the metallic vapor arcing type must be maintained within a certain range to secure the optimum operation thereof. The temperature of the rectifier cannot be allowed to rise above a certain value otherwise the density of the metallic vapor would increase to a point at which back-fires and other disturbances of operation would take place. Such temperature control is best obtained by regulation of the cooling medium such as water supplied to the several portions of the rectifier which are double-walled or are provided with coils through which the cooling medium may flow. The cooling water may be supplied continuously from a suitable source and may be discharged to waste from the rectifier after serving its purpose. If a sufficient supply of water is unavailable or if the available water is unsatisfactory for continuous supply to the rectifier of fresh water by reason of impurities which cause corrosion or deposition of sediments, it is necessary that the same water be recirculated through the rectifier and be recooled in a closed system.

Closed recirculating cooling systems for rectifiers are known in which all of the portions of the system are connected in series with an external cooler. Only a very slight temperature difference is, however, obtainable between the water inlet and outlet of the rectifier when such cooler is used. The recooler must, therefore, be of relatively large size to obtain sufficient heat transfer from the hot water discharged from the rectifier to the atmosphere particularly when the ambient temperature is high. If the allowable rectifier temperature is only slightly above room temperature, it is not economical to use the known recirculating systems. The use of rectifiers in hot climates particularly where sufficient supplies of fresh water for continuous supply for cooling purposes is impossible to obtain is, therefore, dependent entirely on a satisfactory closed recirculating cooling system.

The greatest voltage drop and hence the greatest heat losses in a rectifier occur at the anodes and the surrounding arc guides adjacent the anodes, both of which are heated to very high temperatures. The heat from such portions of the rectifier structure must be removed substantially only by radiation to the adjacent cooled

portions of the structure. The temperature difference between the anodes and the adjacent cooled portions of the rectifier is very high so that the water circulated through such portions may be heated to a relatively high temperature without materially influencing the rate of heat flow between the anodes and the cooled portions of the rectifier. The remaining heat losses of the rectifier, generally conducted through the metallic vapor producing the valve action in the rectifier, are relatively slight and hence the other cooling structural portions must be kept at a relatively low temperature to secure efficient heat transfer due to the temperature difference between such vapor and the cooling portions of the rectifier in contact therewith.

It is, therefore, among the objects of the present invention to provide an electric current rectifier of the metallic vapor arcing type with a closed recirculating cooling system so arranged as to allow the maintenance of the optimum heat transfer from all portions of the rectifier.

Another object of the present invention is to provide an electric current rectifier of the metallic vapor arcing type with a closed recirculating cooling system in which the cooling system is divided into separate circuits cooling different portions of the rectifier structure at different rates.

A further object of the present invention is to provide an electric current rectifier of the metallic vapor arcing type with a closed recirculating cooling system in which the cooling system is divided into separate paths in which the recirculating cooling medium is kept within different temperature ranges.

Objects and advantages other than those above set forth will be apparent from the following description when read in connection with the accompanying drawing which somewhat diagrammatically illustrates one embodiment of the invention in which the portions of the rectifier structure forming paths for the circulation of a cooling medium therethrough are divided into separate circuits through which the cooling medium is circulated at different temperatures.

Referring more particularly to the drawing by characters of reference, the reference numeral 1 designates the double-walled bottom of a rectifier, the bottom being substantially in the shape of a frustum of a hollow cone. The aperture through the bottom 1 is closed by a double-walled plate 2 insulated from the bottom as at 3. The plate 2 and the insulation 3 together form a well to retain a quantity of vaporizable material such as mercury which forms the cathode 4 of the rec-

ifier. A double-walled cylindrical portion 6 extends upwardly from the bottom portion 1 and the open upper end of the cylindrical portion is closed by a double-walled top plate 7 having a 5 cylindrical extension 8 which is also double-walled and forms a dome in which a portion of the metallic vapor in the chamber formed by the bottom 1, side wall 6 and top plate 7 is condensed.

10 A plurality of anodes 11 are arranged to extend into the rectifying chamber from the exterior thereof through the top plate 7, the anodes being insulated from the top plate by the insulators 12 also extending therethrough. Each 15 of the anodes 11 is partially enclosed by a sleeve or arc guide 13 depending from the insulator 12 to adjacent the bottom 1. A coil of tubing 14 is arranged within the rectifier chamber and in the area enclosed by the anodes 11 and closely 20 adjacent the arc guides 13. It will be seen from the drawing that the anodes are arranged closely adjacent the side wall 6.

The bottom 1, cathode plate 2, top plate 7, and condensing dome 8 are connected in series by 25 tubing 16. The dome 8 is connected by tubing 18 with one end of a radiator 19, the other end of the radiator being connected with a cooling medium circulating pump 21 driven by any suitable means. The pump is connected with the cathode plate 2 by tubing 22. The tubing 18 and 22 30 is preferably provided with insulating sections as at 23 and 24 for the purpose of diminishing the degree of electrolytic corrosion when portions of the cooling medium circulating installation 35 are grounded. The use of insulating sections also permits the cooling installation to be kept at ground rather than cathode or tank potential. The above cooling medium circuit provides for the circulation of cooling medium about the cathode 40 4 and through the portions of the rectifier structure which are particularly in contact with the vaporized materials to be condensed to retain the vapor density within the rectifier below a predetermined amount.

45 The side wall 6 and one end of the cooling coil 14 are connected by tubing 31. The other end of the coil is connected by tubing 33 having an insulating section 34, with one end of a radiator 36, the other end of the radiator being connected 50 with a pump 37 for recirculating the cooling medium. The discharge of the pump is connected by tubing 38 having an insulating section 39 with the side wall 6. The above circuit provides a path for the circulation of cooling medium adjacent to and on both sides of the anodes.

55 Both of the radiators are preferably enclosed in a housing 41 through which air is forced by fan 42 driven by suitable means. The heat absorbed by the cooling medium flowing through 60 the several circuits is thus transferred to the current of air blown over and through the radiators and the water is thus recooled. It will be understood that the driving means for the pumps and the fan may be controlled jointly or severally 65 by thermal means associated with the several cooling medium circuits or with the rectifier as is well known.

70 In the arrangement shown, radiator 19 of the cathode-condensation dome circuit in which the cooling medium should be kept at a lower temperature than in the side wall-cooling coil circuit, is arranged between radiator 36 and fan 42. The cooling medium in the latter circuit is thus kept at a higher temperature than in the 75 former circuit. The anodes and arc guides are

thus kept at a higher and more preferable operating temperature which prevents the condensation of mercury vapor thereon than the other portions of the structure on which it is desirable to condense mercury vapor to control the vapor density in the chamber. The recooling structure may be kept much smaller than was possible heretofore under similar conditions thus reducing the construction and installation costs thereof and reducing the space required therefor. It will be understood that the radiators may also be arranged in separate coolers or that the housing 41 and fan 42 may be omitted, it being necessary merely that the cooling medium in the separate paths be kept at different temperatures. 80 85 90

Although but one embodiment of the present invention has been illustrated and described, it will be apparent to those skilled in the art that various changes and modifications may be made therein without departing from the spirit of the invention or from the scope of the appended claims. 95

It is claimed and desired to secure by Letters Patent:

1. In apparatus of the character described, the combination with a casing forming a closed receptacle containing a quantity of vaporizable electrode material and having double walled top, side and bottom portions forming a plurality of chambers for the flow of cooling fluid therethrough, a first cooling system comprising a recooler, a cooling fluid and means for causing the recirculation thereof serially through said recooler and said chambers formed about said top and bottom portions of said casing, a second cooling system comprising a recooler, a cooling fluid and means for causing recirculation thereof through the last said recooler and through said chamber formed about said side wall portion of said casing, and means common to said systems operable to recool said fluid flowing through the second recooler and to simultaneously recool the said fluid flowing through the first said recooler to a lower temperature whereby the said top and bottom wall portions of said casing are maintained at a lower temperature than the temperature of the said side wall portion thereof. 100 105 110 115 120 125

2. In apparatus of the character described, the combination of a receptacle having an aperture therein and being provided with a plurality of double walled portions forming separate passages for the flow of cooling fluid therethrough, a second receptacle containing a quantity of vaporizable electrode material closing said aperture and having a double walled portion forming a passage thereabout for the flow of cooling medium therethrough, a first cooling system comprising a cooling fluid and means for causing recirculation thereof through another of said passages about the first said receptacle, and means common to said systems operable to simultaneously recool said fluids to such different temperatures as to cojointly regulate the rate of vaporization of said material, to affect the direction of flow of vaporized portions thereof and to effect condensation of such 130 135 140 145 said vaporized portions thereof.

3. In combination with an electric current rectifier comprising a casing forming a closed receptacle having bottom, side and top wall portions and containing a quantity of vaporizable cathode 150

material, of chambers formed about the respective said wall portions providing separate passages for the flow of cooling fluid therethrough, a cooling coil supported within said receptacle intermediate the top and bottom portions thereof, a first cooling system comprising a cooling fluid and means for causing recirculation thereof serially through the said chambers formed about the said bottom and top portions of said casing, 10 a second cooling system comprising a cooling fluid and means for causing the recirculation thereof serially through the said chambers arranged about said side wall portion of said casing and through said coil, and means common to 15 said systems operable to simultaneously recool said fluids to such different temperatures as to cojointly regulate the rate of vaporization of said material, to affect the direction of flow of vaporized portions thereof and to effect condensation 20 of such said vaporized portions thereof.

4. In combination with an electric current rectifier comprising a casing forming a closed receptacle containing a quantity of vaporizable
